CLAIM

The ornamental design for an injector nozzle, substantially as shown and described.

DESCRIPTION

FIG. 1 is a perspective view taken from the top, rear, and right sides of an injector nozzle embodying our new design;

FIG. 2 is a right side elevational view thereof;

FIG. 3 is a rear elevational view thereof;

FIG. 4 is a front elevational view thereof;

FIG. 5 is a left side elevational view thereof;

FIG. 6 is a top plan view thereof; and

FIG. 7 is a bottom plan view thereof.
